ELECTRICAL RECEPTACLE

Filed Nov. 14, 1936

FIG. I.

This technical drawing shows a cross-section of a mechanical assembly, possibly a cylinder or pump. The diagram is labeled with numerous numbers, likely referring to parts or steps in the assembly process. Key labels include:

- 5, 6, 3, 18, 19, 2, 4, 91, 17, 15, 16, 31, 33, 38, 28, 29, 30, 22, 46, 24, 5, 31, 34, 30, 35, 41, 33, 29, 33, 18, 2, 19, 18, 4, 33, 42, 11, 16, 1, 34, 38, 6, 23, 21, 6, 32, 25, 15.

FIG. 7

ELECTRICAL RECEPTACLE

Philip E. Hamilton, Beaver Falls, Pa.

Application November 14, 1936, Serial No. 110,934

2 Claims. (Cl. 173—330)

This invention relates to electrical fixtures, and more particularly has reference to outlet receptacles such as are adapted to receive the jacks of attachment plugs.

It is well known that the standard outlet receptacles which are now in use have undesirable features. One of the most important of these features is that these receptacles have been dangerous because they will permit the insertion of various metallic objects, such as hairpins, screw drivers or the like, and numerous persons have received very severe shocks as a result thereof.

Moreover, the slots in the receptacles become filled or clogged with foreign matter, and thus render proper contact difficult and present the possibility of short circuiting.

While many attempts have been made to provide outlet receptacles with a high safety factor, these devices either have been totally ineffective or else so expensive as to render the use of the same prohibitive.

An important object of my invention is to provide an outlet receptacle with a high factor of safety.

Another object of my invention is to provide a receptacle which will prevent possible electrical shock to persons using the same.

Yet another object of my invention is to provide an outlet box which is simple and economical in construction and which will require only slight changes from the present conventional type of receptacle.

Yet another object of my invention is to provide a receptacle which will prevent the entrance of dirt and other foreign matter to the slots.

With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawing means for carrying the same into practical effect without limiting the improvements in their useful applications to the particular constructions, which, for the purpose of explanation, have been made the subject of illustration.

In the drawing:

Figure 1 is a front elevation, partly cut away, of the receptacle, showing it mounted with the usual face plate.

Figure 2 is a view taken along the lines 2—2 of Figure 1.

Figure 3 is a view taken along the lines 3—3 of Figure 2.

Figure 4 is a view taken along the lines 4—4 of Figure 2.

Figure 5 is a view taken along the lines 5—5 of Figure 1.

Figure 6 is a view taken along the lines 6—6 of Figure 1.

Figure 7 is a detail view showing the clip for holding the yoke member to the outlet box.

Figure 8 is a view similar to Figure 2, showing a modified form of my device.

Referring to the drawing, and more particularly to Figure 2, I have shown a conventional outlet box 1, having ears 2 provided with screw threaded apertures 2', the purpose of which will later become apparent. The outlet box is adapted to be positioned in the usual manner in a recess in the wall, or in any other desired location.

The receptacle for the attachment plug comprises a base 3 of insulating material, such as vulcanized rubber or the like. The top face of the base is cut away as at 4, forming a centrally disposed raised portion 5. The sides of the base are also cut away as shown at 5'. Channels 6 and 7, which are diametrically opposed, extend through the base member, as shown in Figure 5. While I have shown a receptacle having two outlets, it is of course to be understood that this is merely for the purpose of illustration and that a more or less number of outlets may be employed if desired. Inasmuch as both of these outlets are of identical construction, I shall confine my description to but one, for the purpose of simplicity.

The channels 6 and 7 are adapted to receive the jacks of an attachment plug (not shown), and there are positioned in the channels resilient contact elements 8 and 9. The resilient contacts are engaged by the jacks when the plug is in operative position.

The resilient contacts 8 and 9 are connected to binding posts 10, which are positioned in the cut away portion 5', by means of metallic conductors depicted generally at 11. Inasmuch as the conductors 11 are of conventional form, it is not necessary to go into detail in regard to these elements.

As shown in Figure 3, the raised portion 5 of the base is provided with laterally extending lugs 12 positioned between the binding posts. It will be appreciated that these members will prevent any possibility of short-circuiting.

Referring to Figures 2 and 5, I have shown an insulating plate, of any suitable material but preferably of fiber, 13, which is positioned at the bottom of the base 3, and which seals the channels 6 and 7. As shown in Figure 5, the insulating plate 13 is of the same width as the base 3.

The base 3 and the plate 13 are mounted in a U-shaped bracket 14 of substantially flat metal plate which extends along the outer face of the plate 13. As shown in Figure 2, the upturned ends 15 of the bracket 14 are provided with tongues 16. The tongues 16 are pressed out of the bracket. The base is cut away as shown at 15 17 so as to permit the tongue 16 to fit over the end of the insulating plate and hold such plate firmly in position. It is obvious that this will prevent any movement of the plate relative to the base and the supporting bracket. The bracket 20 terminates in flanged portions 18 which are provided with apertures 19.

The ends of the bracket 14 fit within channels 20 20 provided in the side of the base 3. These channels prevent any tendency toward relative 25 rotation between the bracket and the base.

The base 3 is also provided with a centrally disposed bore 21 which has a countersunk portion 22 in the raised portion 5. An internally threaded metallic sleeve 23 having a hexagonal head 24 30 is fitted into the bore 21.

The bracket 14 and the plate 13 are provided with centrally aligned openings 25 and 26 through which extend a screw 27 which is screwed into the metallic sleeve for holding the base 3, the insulating plate 13, and the bracket 14, together.

A circular disc or shutter 28 is adapted to fit over each of the outlets of the base 3. Diametrically opposed slots 29 and 30 extend through the disc. A centrally arranged aperture 31 is provided in 40 the lower face of the disc 28. A similar aperture 32 extending at right angles to the aperture 31 is provided in the upper face of the base. A helical spring 33 is removably positioned in these apertures. One of the looped ends 34 of the spring 33 extends into the aperture 31 and the other looped end of the spring 34 extends into the aperture 32. While I have shown the apertures 31 and 32 as being placed at right angles to each other, it is within the scope of my invention to form 50 these apertures in any desired manner, the purpose of the apertures being to afford a means of resiliently mounting the disc on the base. It will be readily appreciated that this spring resiliently opposes any rotation of the disc with respect to the base.

The base 3 and the disc 28 are so assembled that the slots 29 and 30 are 90 degrees out of alignment with the channels 6 and 7. The spring 33, while of course opposing rotation of the disc, does permit rotation of the disc in either direction until the slots 29 and 30 register with the channels 6 and 7. The strength of the spring 33 may be varied, but it is preferably sufficiently strong for the disc 28 to resist rotation except by the jacks of an attachment plug, and in any event the spring is strong enough to return the disc to the position where the slots are out of register with the channels 6 and 7.

In order to hold the disc in proper position with respect to the base 3, I employ a plate designated generally 35. The plate 35 is of the split type and is formed of two sections 36 and 37. As best shown in Figure 4, the plate is divided centrally 75 at its ends, but is divided off-center in the middle

due to the fact that the metallic sleeve 23 extends through the central portion of the base.

Referring now to Figure 4, it can be seen that the disc 28 is provided with a peripheral groove 38 into which the plate 35 is adapted to fit. The groove is of such depth as to permit the disc to rotate, but it will not allow any excess vertical or horizontal movement. It will be appreciated that the use of apertures in the disc and base for positioning the spring is particularly efficacious, as it obviates the securing of the spring to either the disc or base. With this arrangement, the spring can be readily inserted or removed in a minimum of time. The relative heights of the raised central portion 5 of the base 3 and the flanges 18 of the bracket 14 are such that the plate 13 will rest evenly thereon.

In order to secure the disc 28 and the plate 35 to the bracket 14, I employ clips 39 having in-turned edges 40 which pass around the extremities of the plate and the flanged portion 18 of the bracket. In order to secure the disc plate and bracket to the outlet box 1, screws 41 are inserted through the openings 42, 43 and 19, in the clip 39, plate 35, and flange 18, respectively, and are screwed into the aperture 2' in the ear 2 on the outlet box.

A standard cover plate 44 of suitable insulating material, such as hard rubber, having apertures 45 which correspond to the shape of the discs, 30 is secured to the base 3 by means of a screw 46 which is screwed into the upper end of the metallic sleeve 23.

The operation of my device is believed to be apparent from the foregoing description. The 35 slots 29 and 30 of the disc 28 are normally out of alignment with the channels 6 and 7 in the base, and the jacks of an attachment plug are first inserted into the slots 29 and 30; the attachment plug is then rotated in either direction until 40 the slots come into register with the channels 6 and 7, and the plug is then further inserted until it abuts the upper face of the disc. In this position the jacks are in engagement with the contacts 8 and 9, and close the circuit. It should be noted that the jacks of the plug are securely held in operative position, not only by resiliency of the contact elements, but by the action on the jacks, which is caused by the discs and the 45 spring.

When it is desired to disconnect the plug, it is withdrawn from the base, whereupon the disc 28 returns to its inoperative position, in which the slots 29 and 30 are out of alignment with the 50 channels 6 and 7.

In Figure 8 I have shown a somewhat modified form of my device. In this form, instead of employing a metallic sleeve which extends through the base 3, the plate 35 is provided with a central portion having downturned edges 41 provided with screw threads which are in communication with a recess 48, formed in the base 3. The cover plate is secured to the receptacle by merely screwing the screw 45 into the opening 60 46. In this form it is not necessary to secure the base to the bracket by means of a screw which extends through the bracket and into the base.

It will be appreciated that my invention provides an electrical outlet box which will prevent any accidental or careless contact with the electrical contact elements in the receptacle. By the employment of the rotatable discs, access to the contacts within the base can be had only by 75

means of an attachment plug, and accidental shocks are thereby positively prevented.

Inasmuch as the channels 6 and 7 are closed except when the device is in use, no dust or other 5 foreign matter can enter the slots, and thereby impair the utility of the device.

Furthermore, the outlet box can be manufactured quite cheaply, and only slight changes are necessary in order to convert the conventional 10 or standard type of outlet box into an embodiment of my invention.

While I have shown and described the preferred embodiment of my invention, I wish it to be understood that I do not confine myself to the precise details of construction herein set 15 forth, by way of illustration, as it is apparent that many changes and variations may be made therein, by those skilled in the art, without departing from the spirit of the invention, or exceeding the scope of the appended claims.

I claim:

1. An electrical receptacle comprising a body portion, channels in the body portion, an electrical contact member in each channel, a disc-like shutter member having a pair of slots adapted to register with the channels, a peripheral groove around the shutter member, a plate attached to the body portion fitting into said peripheral groove, said plate preventing movement 20 of the shutter away from said body portion, a

slotted aperture in the lower portion of the shutter member, a slotted aperture in the upper portion of the body portion, a helical spring having its ends bent over along its diameter, said spring being positioned with said bent-over portions in 5 said apertures to normally hold the shutter slots out of register with the channels.

2. An electrical receptacle comprising a body portion, a pair of channels extending therethrough, an electrical contact member in each 10 channel, a disc-like shutter member having a pair of slots adapted to register with the channels, said shutter member having a peripheral groove, a plate attached to the body portion and fitting into said peripheral groove and preventing movement 15 of the shutter away from said body portion, said plate being split substantially in the middle into two plate strips, projections on each plate strip, clips for engaging said projections and holding the plate strips together, a slotted aperture centrally disposed in the upper portion of the body portion, a slotted aperture centrally disposed in the bottom portion of the shutter member, a helical spring having its ends bent over along its diameter, said spring being positioned 20 with said bent-over portions in said apertures to normally hold the shutter slots out of register with the channels.

PHILIP E. HAMILTON. 30
